DAGGER LIFTER FOR LOOMS

Boyd H. Bridgman, Spartanburg, S. C.

Application December 17, 1937, Serial No. 180,398

1 Claim. (Cl. 139—187)

This invention relates to an improved dagger lifter, which is particularly adapted for use on high speed looms where it is necessary to release the pressure on the back binder in the shuttle box so that the shuttle may be expelled from a loose box and received into a loose box on the opposite end of the lay. The dagger lifter herein described is an improvement in the structure shown and described in Letters Patent No. 10 2,093,226, issued September 14, 1937.

In high-speed looms when weaving in the neighborhood of one hundred and eighty to two hundred picks or over per minute, there must be a high pressure exerted upon the back binder 15 of the shuttle boxes and the shuttles in order to effectively actuate the protection dagger. Unless this pressure is exerted, the protection dagger will not act quickly enough to cause the loom to be stopped in case of an improperly boxed shuttle or by an empty shuttle box during the beating up or forward stroke of the lay. As stated in Patent No. 2,093,226 it is desirable to have a loose shuttle box from which the shuttle is expelled and a loose box for receiving the shuttle. 20 This looseness within the box may be accomplished by raising the dagger at the proper time and thus relieving the pressure upon the back binder.

It is, therefore, an object of this invention to 30 provide a dagger lifter which is adjustably secured to the frame of the loom, said lifter projecting upwardly and beneath the dagger to cause said dagger to be raised when a loose shuttle box is desired. By adjustably securing the lifter to 35 the frame of the loom, it may be adjusted independently of the frog member, therefore, the time of raising the dagger to provide a loose box may be delayed or advanced as desired.

Some of the objects of the invention having 40 been stated, other objects will appear as the description proceeds, when taken in connection with the accompanying drawing, in which:

Figure 1 is a transverse sectional view through the lay of a loom showing my invention applied 45 thereto;

Figure 2 is a plan view taken along the line 2—2 in Figure 1;

Figure 3 is an elevation of a portion of the loom lay and taken along line 3—3 in Figure 1;

50 Figure 4 is an isometric view showing my improved lifter apart from the loom.

Referring more specifically to the drawing, the numeral 10 denotes the lay of a loom which has the shuttle box mounted at each end on the upper 55 side thereof comprising a box front 12 and a

back binder 13, between which a shuttle 14 is adapted to move when the shuttle is in a boxed position. The back binder 13 is pivoted as in a conventional manner as shown in Patent No. 2,093,226 and is adapted to furnish the necessary guidance for the shuttle as it enters the box. Suitable checking means, not shown, are provided for checking the shuttle when it is positioned in the shuttle box. This checking means may be of the type shown in said patent.

10 As heretofore stated, it is very desirable in high-speed looms that the shuttle be allowed to enter a loose box, but immediately upon its entry the pressure of the binder 13 must be applied to assist the checking means to check the velocity. 15 Also when it leaves the box, this pressure must be released from the back binder so that a quick getaway may be obtained. This pressure is applied, or released, by means of a suitable arm 16 which has its lower end secured to one end of a suitable protection rod 17, said rod extending transversely of the loom and being pivotally mounted in suitable brackets, such as 18. A torsion spring 19 normally holds the upper end of arm 16 against 20 back binder 13.

25 Also mounted on protection rod 17 is a dagger 20, which moves back and forth along the lay as it oscillates from the bold line position to the dotted line position as shown in Figure 1. If, for any reason, the shuttle is not properly boxed, then 30 the arm 16, whose upper end is normally forced against the binder 13 by spring 19, will cause the left-hand end of the dagger 20 to rotate in a counter-clockwise manner and upon the movement of the lay to the left in Figure 1, the lower 35 end of the dagger will contact steel member 21, and cause the frog member 22 to be moved to the left.

40 This frog member is slidably mounted on the frame 23 of the loom and is normally forced to the right and against a stop 24 by means of a suitable compression spring 25. Upon the contact of dagger 20 with the frog steel 21, the frog 45 22 will also move arm 21 to the left and cause this arm to operate the lower end of knock-off lever 28 which in turn will stop the loom.

The parts thus far described are conventional, but it is deemed necessary to disclose this much of the old structure in order to more effectively explain the purpose of my invention. As heretofore stated, when the lay is in a rearward or dotted line position, it is desirable that the pressure upon the back binder be relieved so that an incoming or an outgoing shuttle may have a loose box from which to enter or to leave.

- This pressure is relieved by providing a suitable dagger lifter 30 which has a base portion 31, said portion being secured to the loom frame 23 by any suitable means, such as bolt 32. The bolt 32 penetrates the slot 30a in the lifter and slot 24a in the stop member 24 and the loom frame 23. The lifter has an upstanding arm 30b integral therewith, said arm being adapted to project over the top of frog 22. The position that this overhanging portion 30b occupies relative to the frame of the loom determines the time at which the dagger 20 is raised to cause the pressure to be relieved from the back binder 13. Therefore, the slot 30a is provided so that a certain amount of latitude may be had in the adjustment. Since both the stop member 24 and the lifter 30 are secured to the frame 23 by bolt 32, it is evident that when the bolt is loosened to adjust one of the members, that the other may be adjusted also.
- It is, therefore, seen that I have provided a dagger lifter which is adjustably mounted relative to the frame of the loom, and which is independent of the frog member.
- In the drawing and specification there has been set forth a preferred embodiment of the invention, and although specific terms are employed,

they are used in a generic and descriptive sense only, and not for purposes of limitation, the scope of the invention being set forth in the appended claim.

I claim:

In a loom provided with an oscillating lay and having a shuttle box on each end of the lay, each shuttle box being provided with a movable binder, said lay being provided with a protection rod provided with a dagger, said loom having a frog adapted to be engaged by the dagger in the absence of a shuttle in a shuttle box for stopping the loom, said protection rod having an upstanding arm engaging the binder and a torsion spring on the protection rod for applying pressure to said arm for exerting pressure on the binder, means for relieving pressure of said torsion spring on said binder at a certain point in the oscillation of the lay, comprising a member mounted on the loom frame for adjustment relative to the frog and extending over a portion of the frog to engage the dagger and raise the same while a shuttle is being expelled from a shuttle box in one end of the lay and being received in the shuttle box in the other end of the lay.
